SCREENING AND REFINING OF FIBER

Filed June 17, 1932

UNITED STATES PATENT OFFICE

1,970,330

SCREENING AND REFINING OF FIBER

William H. Mason, Laurel, Miss., assignor to
 Masonite Corporation, Laurel, Miss., a corpora-
 tion of Delaware

Application June 17, 1932, Serial No. 617,786

20 Claims. (Cl. 92—26)

My invention relates to screening and refining, and particularly to a process and apparatus that eliminates need for separate screening, and combines the functions of screening and refining.

A principal object of the invention is the provision of means for performing a screening operation which is entirely free from clogging and permits the free passage of pieces or particles 10 which are already below a predetermined size, without expenditure of unnecessary refining work thereon, and which is also adapted for reducing any coarser pieces or particles below such limiting size, whereupon the same are freely and 15 quickly passed through along with the originally smaller pieces or particles, with the minimum of work uselessly (or harmfully) expended in producing unnecessary refinement.

The invention is of general application, but 20 apparatus for carrying out my new process is especially well adapted for screening and for refining of vegetable fiber for manufacture of fiber boards, as for example, porous insulation board made by drying a wet lap of the fiber, or 25 hard dense board made by hot-pressing and having a specific gravity of about .9 to about 1.1, may be advantageously made from such fiber.

Fiber when used in making fiber boards need 30 not be highly refined, but does require a sufficient state of refinement or subdivision of the coarser parts to permit the fiber to be readily formed from water into a smooth blanket or sheet or so-called wet-lap, as in a Fourdrinier 35 or equivalent wet machine.

When fiber is made from hard or soft woods, as for example by progressive discharge through constricted outlets from under high pressures, as taught in my Patent No. 1,578,609, granted on 40 March 30, 1926, the resulting so-called gun-fiber contains quite a large proportion, as for example say 50% of "fines" which are already sufficiently reduced in size so as to be ready for use and require no further refining treatment, 45 either in the way of reduction in size or in length, and there is also a proportion of coarser material in the nature of fiber bundles, which requires refinement for securing reduction to the predetermined size found necessary to get 50 a smooth, even wet-lap, while at the same time it is desirable to maintain the fiber length to the greatest possible extent.

With the present invention it becomes possible to avoid the necessity of preliminary screening for separation of the finer from the coarser

pieces or particles, and to put the entire fiber material, such as gun fiber for example, with only perhaps removal of some chip-like pieces, through a single treatment which performs the screening function at the same time that it does 60 the refinement work required to reduce the larger pieces to the desired size. Of course, if the material treated is all relatively coarse, then the screening action is confined to removal of 65 the fines as rapidly as produced through the refining action performed on the coarse fiber.

With my invention the entire work done on the pulp or other material to be treated is accomplished in a very short path of travel of the material, usually a travel only an inch or two in length 70 between relatively rotating surfaces which are preferably roughened, and a number of such possible paths of travel are preferably provided, arranged in parallel, whereby increased rapidity of flow can be obtained and large quantities of material treated.

I preferably obtain such paths of travel in parallel by providing same between rotating ring-shaped members, and arrange such members in sets which are rotatable relative to one another, 80 as for example, one set may be stationary and the other rotatable with respect thereto, or one set may rotate in one direction while the other rotates in the opposite direction, or both may rotate in the same direction, but at different speeds. 85

I have illustrated a preferred form of apparatus in the accompanying drawing, in which—

Figure 1 is a longitudinal sectional view, and Fig. 2 is a fragmentary detail sectional view 90 on the line 2—2 of Fig. 1.

The illustrated apparatus is contained in a hollow circular casing 10, made in two, preferably substantially like, portions 12 and 14 secured together along the medial line by bolts 15 for ease in assembly and take-down.

One of the casing members 12 is provided with an axial opening 16 for admission of the pulp to be treated, and the other member 14 provided with a similar preferably axial outlet 18 for the exit passage of the screened and/or refined pulp.

Conduit necks such as 20 and 22 with flanges 24 and 26 may be supplied for the convenient attachment of supply and outlet conduits, and are preferably directed at right angles to the axial line of the casing so as to be out of the way of the shaft and operating mechanism. The pulp may be pumped or supplied under a gravity head if desired.

In the simplest form, the casing is provided 110 with a stationary spider 28 comprising radial

arms 30 with openings 32 therebetween, the spider arms 30 being connected by inner and outer ring portions 34 and 35, the former resting against and backed up by the casing collar 36 containing the holes 37 through which the material passes on its way to the axial outer passage 18. I provide a series of concentric refiner rings 38 and attach same to the spider 28 as by bolting same within annular grooves or notches 40 provided to receive and hold same. Such rings 38 are widest at their bases 42 where they are bolted to the spider 28, and they have preferably like tapering sides 44, 44 terminating in a narrow edge portion 46 on the face thereof furthest from the spider 28. The outermost ring 38' is preferably tapered only on its inner face and has a flat outer face which is received within groove parts 39, 39' in the casing members 12 and 14 respectively, and securely clamped in place and held against rotation by the bolts 15 that secure the two halves of the casing together. The width of the taper faces 44 is but a small fraction of the ring diameter.

The shaft 50 extends axially through the casing 10 with provision against leakage as by means of glands 52, 54, and the drive means therefor, consisting preferably of an electric motor with a reduction gear (not shown), has driving connection to the shaft 50 by means of a slide coupling 55 which will permit longitudinal movement of the shaft 50 without interfering with the drive.

Provision is made preferably beyond the opposite or exit side, of the casing 10, for adjusting the shaft 50 longitudinally, for a purpose to be referred to later, and in the form shown, shaft 50 runs in a ball bearing 60, and the inner annular bearing member 62 thereof is attached to such shaft 50 so as to be restrained from longitudinal movement with respect thereto. As shown this connection consists in interposing the inner bearing member or ring 62 of the ball bearing 60 between the shoulder 64 of the shaft 50 and the flanged plate 66 bolted to the end of shaft 50.

The means for moving the bearing 60 and thereby adjusting the shaft 50 endwise is attached to the casing 68 which receives the outer member 70 of the ball bearing, and preferably consists of a screw threaded shaft 72 secured to the casing member of the ball bearing at 74, and having the hand wheel member 75 screwed thereon and having its hub provided with a groove 76 to receive a preferably split collar 78 of the bearing housing 80, said hand wheel 75 thus serving when turned for moving the ball bearing 60 forward or back and thereby adjusting shaft 50 longitudinally, and the screw threaded locking wheel member 81 can be tightened up for locking the parts in various adjusted positions.

The shaft 50 is formed with a shoulder 51 and has keyed thereto within the casing 10, a spider 82 having radial arms 84, a hub 86 engaging shoulder 51, and an outer connecting ring 88 with openings 89 between the radial arms. (The openings 32 in the stationary spider 28 are similar to the openings 89 of rotatable spider 82 as shown in Fig. 2.) The concentrically arranged refiner rings 90 are bolted to spider 82, being received in positioning grooves or notches 92. These rings 90 are of a size to face the openings between the refiner rings 38 of the stationary spider 28, and said rings 90 have short tapering outer face portions 94 adapted to enter between the tapered parts 44 of the stationary rings 38, but are rather narrow and flat sided at their rearward portions so as to leave the tapering entrance passages 96 between them and such tapered face parts 44, and so make a relatively wide mouth

at 96 with converging walls for easy entry of any coarse pieces of material between the co-acting tapering parts.

By adjusting the shaft 50 endwise by means of the hand wheel 75 provided for such purpose, the spider 82 may be adjusted with respect to spider 28, and the annular passages at A between the tapered rings 38 and 90 may be made as wide or narrow as desired, and the parts locked in such position by means of locking wheel 81. The length of the passages A, which determines the distance the material travels in passing through the passage, is relatively short and depends principally on the width of the taper faces of the refiner rings as 44, 94. Both the length and width of the passages A are preferably a small fraction of the annular passage diameter.

The pulp or other material to be treated and supplied as by pumping or under gravity head to the inlet side, in order to reach the outlet side must pass through the annular passages A between the refiner rings adjusted to whatever predetermined spacing may be desired.

The fiber is handled in low concentration in a pulp with water, the content of dry fiber by weight being desirably under 4% by weight of the total pulp and preferably around 1/2% or 1% thereof.

The pieces or particles of fibers or bundles of fibers which are sufficiently small pass with the water stream freely through the annular passages A. In the case of fibrous materials too coarse to pass through immediately, there is a rolling action thereon obtained between the co-acting faces of the refiner rings which is favorable to the production of a long fiber product and as soon as the breaking-down and refining action has proceeded with the small bundles of fiber to such extent that they are sufficiently fine to pass through the openings A, they pass therethrough and go on with the current, leaving other coarser parts to be similarly reduced and sent on to the exit side of the mechanism.

With my invention numerous features of advantage are obtained. The rings can be made of metal, stone composition and the like, and can be readily removed for roughening to provide attrition to any desired extent. Substantially any desired capacity can be obtained by choice of the number of refining and screening rings. Substantially any desired treatment may be given as for example, the new machines may be arranged in a series of two or more with successively closer settings. No clogging can take place as happens with certain types of screens as the walls of the passages are in relative movement so that the stock is kept moving and passes through with the current.

Unnecessary and possibly harmful overrefining is eliminated, no separate screens are needed, and other items of advantage include saving in power requirements, production of long fiber refined pulp, high capacity, simplicity, cheapness and accessibility of parts.

I claim:

1. In a combined screening and refining apparatus for unevenly comminuted material, a pair of relatively rotating members each provided with a plurality of concentric rings having taper faces, the rings on the respective members being arranged to provide a plurality of passages therebetween for material treated.

2. Apparatus as in claim 1, in which the width of the taper ring faces is a small fraction of a ring diameter.

3. Apparatus as in claim 1, in which the mem-

- bers of the pair are movable toward and away from one another, and in which means are provided for producing such relative movement and thereby adjusting all the rings of a set simultaneously with respect to those of the other set.
4. In a combined screen and refiner for pulp of vegetable fiber or the like, a casing provided with inlet and outlet, two sets of relatively rotating substantially concentric ring members with co-acting taper faces within the casing and between which material traversing the casing from inlet to outlet must pass, and means applied to all the rings in a set for producing relative adjustment of said ring sets toward and away from one another.
5. Apparatus as in claim 4, in which the width of the taper ring faces is but a small fraction of the ring diameter.
6. Apparatus as in claim 4, in which one of the sets of concentric rings is fixed in the casing, and the other is rotatable therein.
7. Apparatus as in claim 4, in which one of the sets of tapered rings is fixed in the casing and the other is rotatable therein, with means for adjusting the rotatable set of rings toward and away from the fixed set of rings, said adjusting means applying alike to all the rings of the rotatable set.
8. Apparatus for screening and refining of vegetable fiber and the like pulp, comprising a casing with inlet and outlet, a shaft extending axially through said casing, a spider fixed in the casing, concentric taper-faced rings on said spider, a second spider fixed on the shaft to turn therewith and facing the first named spider, a series of concentric taper-faced rings on said last named spider, and adapted on longitudinal movement of the shaft to be received between the taper-faced rings on the first named spider, and means for the longitudinal adjustment of said shaft.
9. Apparatus as in claim 8, in which the width of the taper faces of the ring members is but a small fraction of the ring diameter.
10. Apparatus as in claim 8, in which the rings on the fixed spider have taper faces extending throughout the width thereof, while the rings on the rotatable spider have tapered faces extending through part of their width and parallel faces throughout the remainder of their width, whereby the annular orifices between the rings are principally parallel-sided but have entrance portions with converging sides.
11. In a combined screening and refining apparatus, a casing provided with inlet and outlet, two sets of relatively rotating ring members in said casing with co-acting taper faces, providing a number of passages therebetween for material treated having a width which is a small fraction of a part of the ring diameter, said passages having an enlarged mouth part converging to a relatively narrower portion with substantially parallel walls.
12. The process of treating vegetable fiber to produce limited refinement of coarse fiber bundles while substantially maintaining the fiber length and to pass along the finer portions freely without material refinement thereof, which comprises passing same in low concentration in water through a substantially annular passage of substantially like width all the way around, and of length which is a small fraction of the diameter, while subjecting the coarser portions to attrition by producing relatively rotary movement of the substantially continuous walls defining the annular passage.
13. Process as in claim 12 in which dry fiber is under 2% of the pulp by weight.
14. Process as in claim 12 in which the watery pulp is passed through an annular passage widest at its mouth.
15. Process as in claim 12 in which by weight dry fiber is under 4% of the pulp and the watery pulp is passed through an annular passage widest at its mouth.
16. Process as in claim 12 in which the watery pulp is passed through a plurality of annular passages concentrically disposed and which afford a plurality of paths in parallel for the travel of the pulp.
17. Process as in claim 12 in which the watery pulp is passed through a plurality of annular paths widest at their mouths and which are concentrically disposed and afford a plurality of paths in parallel for the travel of the pulp.
18. Process as in claim 12 in which by weight dry fiber is under 2% of the pulp and the watery pulp is passed through a plurality of annular passages widest at their mouths and which are concentrically disposed and afford a plurality of paths in parallel in the travel of the pulp.
19. A combined screening and refining apparatus for comminuted material in low concentration in water comprising a pair of relatively rotating concentric members providing between them an annular passage of substantially uniform width all the way around, which width is a small fraction of the annulus diameter, and the length of which passage is likewise a small fraction of the annulus diameter, and supply and exit means for watery pulp of the comminuted material on the respective sides of the short, narrow, annular passage.
20. The apparatus of claim 19, and in which the member defining one wall of the passage is fixed, and the member defining the other wall is rotatable.
